PROPANE DEASPHALTING OF CRUDE
RESIDUA OF HYDROCARBON OILJohn G. Ditman, Flushing, N. Y., assignor to
Foster Wheeler Corporation, New York, N. Y.,
a corporation of New York

Application December 21, 1950, Serial No. 201,932

3 Claims. (Cl. 196—14.46)

1

This invention relates to separation of asphalt from crude residua in the refining of hydrocarbon oils and more particularly to the propane deasphalting of said crude residua.

In propane deasphalting processes commonly used in refining of petroleum for the separation of asphalt from crude residua, difficulty is encountered due to foaming in stills used to recover propane from deasphalting oil and asphalt products particularly when the stills are operating at relatively low temperatures and using steam as the source of heat. Various processes for suppressing foam have been used, one of which processes involves spraying propane into the top of a tower used as a still. The foam, in this process, is broken by the liquid spray. A disadvantage of this said one process is that the quantity and temperature of the injected liquid is critical. For example, should an excessive quantity of liquid be sprayed into the tower, the temperature thereof may be depressed excessively by the evaporation of the liquid propane thus aggravating the foaming condition. In a second known process, coils or tubes carrying high pressure steam are disposed in the upper part of a tower operating as a still to superheat the vapor thus breaking the foam. This second process has not been entirely successful in that it is not possible to include sufficient heating surface, namely, coils or tubes, to provide the necessary superheat required.

In the present invention, feed comprising a mixture of propane deasphalting oil and propane is heated to a temperature at which a substantial portion of the propane is evaporated. The liquid and vapor mixture is then passed into a distilling tower in which the vaporized propane flows upwardly, while the liquid passes downwardly into a catch-pan and thence is conducted into a heater where the temperature thereof is raised to a degree substantially higher than that to which the feed is heated in the first-mentioned heater and at which degree more of the propane is vaporized. The mixture of vaporized propane and deasphalting oil so heated is thereafter returned to the lower part of the column wherein the vapor passes upwardly while the deasphalting oil passes downwardly and is conducted to a stripper. A portion of the hot deasphalting oil from the bottom of the tower is recirculated to the upper part thereof where it is projected downwardly in a spray and into intimate contact with the aforesaid rising vapors. Since the recirculated oil is at a higher temperature than the rising vapors, efficient heating of the vapors

2

by direct heat exchange relationship will result. At the same time, the spray affords mechanical breaking of the foam. Propane vapors are thereafter removed from the top of the tower and passed to a condenser.

The invention will be understood from the following description when considered in connection with the accompanying drawing in which the single figure shows diagrammatically and partly in section suitable apparatus for performing the process of the invention in one embodiment thereof.

Referring to the drawing, feed which comprises a mixture of deasphalting oil and propane, is passed through a conduit 10 to a low pressure steam heater 11 wherein the mixture is heated to a degree at which a substantial portion of the propane in the mixture is evaporated under the prevailing pressure. The temperature to which the mixture would normally be heated would be 220° F. After heating, the mixture of vapor and liquid from heater 11 flows through conduit 12 into distilling tower 13 at an intermediate point of said tower and below a baffle 14 which extends transversely of the tower and has a vapor passage 15 therein which passage communicates with an upper chamber 16 in the tower. A catch-pan 17 is positioned within the tower below baffle 14 but in spaced relationship with the bottom 18 of the tower thereby dividing said tower into an intermediate chamber 19 and a lower chamber 20. Catch-pan 17 has a riser passage 21 in the central portion thereof which extends upwardly into intermediate chamber 19 of the tower, said riser having a deflector 22 positioned thereover which deflects gases flowing upwardly through the riser from chamber 20 into said intermediate chamber 19.

The liquid passing downwardly through intermediate chamber 19 from conduit 12 is caught by catch-pan 17 and flows therefrom through pipe 23 into a high pressure steam heater 24. In the heater 24, the liquid is heated to a degree substantially higher than that to which the mixture is heated in heater 11 so that more of the propane therein is vaporized. The degree to which the mixture is heated would normally be approximately 320° F. The mixture of vapor and liquid from heater 24 is passed into the lower chamber 20 of tower 13 through conduit 25 which communicates with the tower below catch-pan 17. Vapors entering the tower through conduit 25 pass upwardly through riser passage 21 and thence are deflected into intermediate chamber 19 of the tower thereafter to pass upwardly with

vapor from pipe 12 through passage 15 in baffle 14 whence the vapors enter upper chamber 16 of the tower.

The hot deasphalted oil flows downwardly from conduit 25 into the bottom 18 of the tower and is withdrawn therefrom through an outlet conduit 26, said deasphalted oil thereafter being passed to a steam stripper wherein the final traces of propane will be removed therefrom.

A portion of the deasphalted oil flowing through conduit 26 is recirculated by a recirculation pump 27, which has its suction in communication through a pipe 28 with conduit 26 and has its discharge in communication with a spray 30, through the conduit 29 which spray 30 is in upper chamber 16 of tower 13 and above baffle 14.

Spray 30 directs hot deasphalted oil, which oil is at approximately 320° F. downwardly and into intimate, direct heat exchange relationship with the rising vapors in upper chamber 16 of tower 13. As shown, the hot deasphalted oil is passed into a bubble tray 31 in chamber 16 which tray has risers 32 with caps 33 thereon and a downspout 34. The hot oil flows onto tray 31 and gases, which pass into upper chamber 16 through passage 15, flow through risers 32 and are directed downwardly and into intimate contact with the oil on said tray by caps 33. After said gas has thusly passed in contact with the oil on the tray, said oil flows downwardly through downspout 34 onto baffle 14. As the rising vapors are at a temperature of approximately 220°-230° F. and the recirculated hot deasphalted oil is at approximately 320° F., efficient heating of the vapors by intimate and direct heat exchange relationship results. At the same time, the spray of hot oil from spray 30 affords mechanical breaking of foam. The superheated propane vapors pass from upper chamber 16 through conduit 35 and are conducted to a condenser, not shown.

Any foam, therefore, which forms in tower 16 is suppressed by the superheating of the propane vapors passing in contact with the spray of hot oil and also by the breaking of said foam by the spray of hot non-evaporating liquid.

It will be apparent that various modifications may be made in the form of the apparatus herein disclosed and in the steps of the method herein described without departing from the spirit of the invention which is not to be limited except by the scope of the appended claims.

What is claimed is:

1. In the propane deasphalting of crude hydrocarbon oil residua having asphalt therein, the process of recovering propane from a liquid mixture of propane deasphalted oil and propane and suppressing foaming encountered in said process which comprises heating said mixture in a heating zone to substantially 220° F. at which temperature a portion of the propane therein is vaporized, passing vapor and heated liquid from the heating zone into a distilling zone, flowing liquid from the distilling zone to another heating zone wherein said liquid is heated to substantially 320° F. at which temperature more of the propane in the liquid is vaporized, flowing residue liquid and vapor from said other heating zone into a lower part of the distilling zone, superheating said vapor in the distilling zone by spraying a portion of said residue liquid heated to substantially 320° F. into contact and direct heat exchange relationship with said vapor in heat exchange relationship with said vapor in an upper part of the distilling zone to cause

suppression of foaming in the latter, and withdrawing vapor from the distilling zone after said vapor has passed in heat exchange relationship with the residue liquid.

2. In the propane deasphalting of crude hydrocarbon oil residua having asphalt therein, the process of recovering propane from a liquid mixture of propane deasphalted oil and propane and suppressing foaming encountered in said process which comprises heating said mixture in a heating zone to substantially 220° F. at which temperature a portion of the propane therein is vaporized, passing vapor and heated liquid from the heating zone into an intermediate zone of an elongated substantially vertically extending distilling zone having an upper zone, an intermediate zone and a lower zone, the lower zone and intermediate zone being in communication with one another so that vapor will rise therefrom and pass into said zone, flowing liquid from the intermediate zone of said distilling zone to another heating zone wherein said liquid is heated to substantially 320° F. at which temperature more of the propane in the liquid is vaporized, flowing residue liquid and vapor from said other heating zone into the lower zone of the distilling zone, superheating said vapor in the distilling zone by spraying a portion of said residue liquid from said lower zone into contact and direct heat exchange relationship with the vapor in the upper zone to cause suppression of foaming in the distilling zone, and withdrawing vapor from said upper zone of the distilling zone after said vapor has passed in heat exchange relationship with said residue from the other heating zone.

3. In the propane deasphalting of crude hydrocarbon oil residua having asphalt therein, the process of recovering propane from a liquid mixture of propane deasphalted oil and propane and suppressing foaming encountered in said process which comprises heating said mixture in a low pressure steam heating zone to substantially 220° F. at which temperature a portion of the propane therein is vaporized, passing vapor and heated liquid from the low pressure steam heating zone into an intermediate zone of an elongated substantially vertically extending distilling zone having an upper zone, an intermediate zone and a lower zone, the lower zone and intermediate zone being in communication with one another so that vapor will rise therefrom and pass into said upper zone, flowing liquid from the intermediate zone of said distilling zone to a high pressure steam heating zone wherein said liquid is heated to substantially 320° F. at which temperature more of the propane in the liquid is vaporized, flowing residue liquid and vapor from said high pressure steam heating zone into the lower zone of said distilling zone, superheating the vapor in the distilling zone by spraying a portion of said residue liquid into contact and direct heat exchange relationship with the vapor in the upper zone to cause suppression of foaming in the distilling zone, and withdrawing from the upper zone of said distilling zone the superheated vapor.
